US00D995116S

(12) **United States Design Patent** (10) **Patent No.:** **US D995,116 S**
(45) **Date of Patent:** **** Aug. 15, 2023**

(54) **ARTICLE HOLDER**

(71) Applicant: **CT Design LLC**, Sherman Oaks, CA
(US)

(72) Inventor: **Chen Turgaman**, Jerusalem (IL)

(73) Assignee: **CT DESIGN LLC**, Sherman Oaks, CA
(US)

(**) Term: **15 Years**

(21) Appl. No.: **29/756,624**

(22) Filed: **Oct. 29, 2020**

Related U.S. Application Data

(63) Continuation-in-part of application No. 29/698,696, filed on Jul. 18, 2019, now Pat. No. Des. 982,329.

(57) **CLAIM**

The ornamental design for an article holder, as shown and described.

DESCRIPTION

FIG. 1 is a top, left-side perspective view of an article holder showing our new design;

FIG. 2 is a front elevation view thereof;

FIG. 3 is a rear elevation view thereof;

FIG. 4 is a top view thereof;

FIG. 5 is left side elevation view thereof; and,

FIG. 6 is the view of FIG. 2 with environment inserted into the article holder.

The broken lines in FIG. 3 depict portions of the article holder that form no part of the claim. The broken lines in FIG. 6 depict environment and form no part of the claim.

1 Claim, 4 Drawing Sheets
